UNITED STATES PATENT OFFICE

ERASTUS BARNES BARKER, OF ORANGE, NEW JERSEY, ASSIGNOR TO L. A. MYERS, JR.,
INC., OF NEWARK, NEW JERSEY, A CORPORATION OF NEW JERSEY

DESIGN FOR A BUCKLE

Application filed July 6, 1929. Serial No. 31,959. Term of patent 7 years.

To all whom it may concern:

Be it known that I, ERASTUS BARNES BARKER, a citizen of the United States, residing at Orange, in the county of Essex and State of New Jersey, have invented a new, original, and ornamental Design for Buckles, of which the following is a specification, reference being had to the accompanying drawing, forming part hereof.

I claim:—

The ornamental design for a buckle, as shown.

ERASTUS BARNES BARKER.
